C. A. Wilson,

Rotary Steam Valve.

Nº 11,073.

Patented June 13, 1854.

UNITED STATES PATENT OFFICE.

CHARLES A. WILSON, OF NEWPORT, KENTUCKY.

OPERATING VALVES FOR STEAM-PUMPS.

Specification of Letters Patent No. 11,073, dated June 13, 1854.

To all whom it may concern:

Be it known that I, CHAS. A. WILSON, of the city of Newport, county of Campbell, and State of Kentucky, have made a new 5 and useful Improvement in the Mode of Working Valves for Steam-Pumps; and I do hereby declare that the following is a full and exact description thereof, reference being had to the accompanying drawing 10 and to the letters and figures of reference marked thereon.

My improvement relates to a conical valve and seat bolted on the side pipe in the same manner that steam chests are in 15 other engines. The taper of this valve and seat is enough to keep the valve from sticking, at the same time keeping the smaller ends of this valve and seat of the same diameter of the steam pipe which is attached on 20 the small end of said seat. The valve has a port bored or cast in the smaller end of the same diameter of the steam pipe. This receiving opening runs in along the center of said valve until it reaches the extreme edge 25 of two ports which run across through the center of said valve, corresponding, with two ports which are in the seat one breadth of themselves below the center of said seat, so that when the valve is on its center the 30 steam can not enter either of these ports in the seat so that when the valve moves either way it must open a port.

The exhaust opening of this valve is a 35 flattened place or cavity on the lower side of said valve wide enough to cover the exhaust in the seat and one of the steam ports at the same time so that the spent steam may escape freely. This escape opening runs down through the bottom of the seat 40 and into an opening which has its outlet in the side of the side pipe under the small end of said valve seat. The above mentioned ports which are in the seat run down through the sides of said seat to two corresponding ports in the side pipe. The above 45 mentioned ports run across through the center of said valve and balance each other with the exception of the taper which causes them to have some pressure outward on the valve 50 and they being in the center on each side of said valve prevents them from pushing the valve to either side of said seat. The pressure of the above mentioned port or opening running along in the center of the valve to 55 the two above mentioned cross ports pushes the valve from its seat. This is provided

for by having two large lugs or ears cast on the sides of the large end of said seat directly opposite to each other, so that when a line is drawn through the center of those 60 lugs it will cross the exact center of said valve seat. To these lugs two columns are screwed to the outer ends of which is an arch in the center of which is an adjustable steel screw which screws against the end 65 of the valve stem which is in the exact center of the large end of said valve, projecting out toward said arch. This stem may have a steel plug fastened in it for the adjustable screw to screw against to prevent 70 its wearing; this adjustable screw is used to adjust the valve so that it may work free under any reasonable pressure; on the large end of said valve are two jogs running in toward said stem, near enough however to 75 leave a recess between said steam and said jogs in which recess the boss on a lever fits; this lever having an eye or hole through said boss which work on said stem and the boss in said recess; these jogs are so ar- 80 ranged that when the lever is thrown to the right it catches on the upper edge of the right jog and on the lower edge of the left one (the same to the left.) This lever is loaded at the top with balls a large one and 85 a small one. The large one is fastened to or on the top of the lever and the small one hinged to the top of it, so that when the large one strikes its resting place the small one falls or shackles over and catches the re- 90 bound of the large one, thus producing a dead stroke instead of having the rebound which would be the case if there was but one ball. This lever is guided by and traverses 95 in a slotted segment at its top end, this segment is cast on the two resting studs of the large ball. These resting studs are hollow for about an inch down from the top. These hollows are filled with wood to which are tacked or nailed india-rubber. This is to prevent the sound the ball would make in falling. These studs are screwed to the side of the side pipe. Near the lower end of these studs are two bearings for a slotted 100 rod to work in. The lower end of the above mentioned lever passes through this slot in said rod. The slot in this rod is equal to half the traverse of this end of the lever. This allows the lever when carried to its center to fall clear of all appendage with 105 its weight and momentum against the jogs as above mentioned; thus making sure of

the opening of the valve, the jogs being so arranged that the lever passes its center some distance before it strikes them, unlike that of Hartin's water meter, the tumbling lever of which has to drag after it the rod that gives it motion, mine falling clear of all appendage and having no fulcrum, the valve being the center of motion, the lever being loaded with two balls for preventing the rebound the resting studs for the large ball; the jogs being so arranged as to receive the power applied to open the valve instead of his slotted plate. In fact, the whole principles involved in the two things differ so widely and there being applied to different purposes, that for which mine is intended his will not do. I think and feel convinced that mine is an improvement far superior to his and being used for a different purpose I cannot see any reason why I shall not obtain Letters Patent for it.

The above said slotted rod has attached to it by a flexible joint a rod which is attached to the upper arm of the tumbling shaft. This tumbling shaft is situated across the center of the stroke of the piston rod and has an arm running down through a slot in another rod which has two adjustable nuts on each end for the knocker to strike; this knocker is screwed on the piston rod with a pinching screw. It has a fork on one side of it pointing upward, which fork straddles the rod with the adjustable nuts on it. These nuts are jammed by having ferrules on the rod equal in length to the traverse of said rod, against the outer ends of which other nuts are screwed. The distance between these adjustable nuts is something less than the stroke of the piston, so that when the knocker strikes these nuts it moves the rod in the same direction that the piston rod is traveling, moving the lower arm of said tumbling shafts the same, and the upper one in an opposite direction, pulling the rod attached to it, which pulls the lower end of the lever in the same direction, moving the upper end with the balls in the opposite way until it passes its center when it falls with its momentum and weight against the jogs of the valve and opening it as above as stated. Fig. 4 shows another way for this lower rod to be worked. This is done by letting the rod pass through the cylinder head and through the head of the pump, having the pistons of the cylinder and the pump to strike it alternately the same as the knocker does in the other. This rod has a long screw on its center so as to fasten on an arm between two nuts, which is also fastened to the upper slotted above mentioned, thus doing away with tumbling shafts and fixtures.

Fig. 1, represents a side elevation of steam cylinder and pump showing the man-

ner of operating the valve by means of the lever, balls, and slotted rod. Fig. 2, represents a transverse sectional view of the steam cylinder and its attachments, showing the ports in the valve and seat, the valve being represented in this view by a longitudinal section. Fig. 3, is a front view of the knocker. Fig. 4, represents another plan compared with that in Fig. 1 for working valve. Fig. 4 also shows a transverse section of the valve and the ports.

1 is a steam cylinder.

2 is the pump.

3 is the piston rod.

4 is the lower rod for moving valve, having the lower arm of the tumbling shaft pass through a slot in it. 5 represents the stands on which it has its bearings.

6 is the knocker for moving valve and rigging.

8 is the lower arm of the tumbling shaft.

9 is the upper arm of the same.

10 is the rod connecting the upper arm of tumbling shaft to the slotted rod.

11 is the slotted rod for moving the lever. 90

S S S is the length of the slot.

12 is the lever with its lower end running through the slot.

13, is the space for the lever to move in before the striking the jogs.

14, 14, are the two jogs with the lever lying against the upper edge of the right one and the lower edge of the left one as before stated.

15 is the large ball lying on its resting stud.

16 is the small ball.

17, 17, are the two resting studs. 18, 18, shows the india rubber nailed to the wood in them.

19 is a slotted segment which guides the lever.

20 is the adjustable screw.

21 represents the flat place in the lower part of the valve for the exhaust port.

22, 22, shows the two cross ports in the valve.

23 is the port or opening running in along the center of the valve to the cross ports.

24 is the steam pipe.

25 is the exhaust port.

26 is the stem of the valve.

13 in the longitudinal section is the valve.

30 in Fig. 4, shows the rod passing through the cylinder head and pump head.

31 in Fig. 4 represents a stiff arm fastened to this rod, also fastened to the slotted rod, which 32 represents in this view.

What I claim as my invention and desire to secure by Letters Patent, is—

1. The double weighted lever, having one fixed, and one jointed weight as described, for opening and closing the valve instantaneously, without a rebound, at the end of each stroke of the piston.

2. I also claim connecting the slanted rod or its equivalent, with the valve by means of the weighted lever and the jogs on the valve, to allow the valve to remain stationary until the piston is at the point of finishing its stroke and then instantly opening and closing them by the weighted lever—the lever turning freely on its fulcrum causing no motion of the valve thereby.
- 5 CHAS. WILSON.
